UNITED STATES PATENT OFFICE.

WILLIAM PERCY SIMPSON, OF OVERTON, PENNSYLVANIA.

CLOTH-WINDING MACHINE.

SPECIFICATION forming part of Letters Patent No. 542,024, dated July 2, 1895.

Application filed February 14, 1895. Serial No. 538,414. (No model.)

To all whom it may concern:

Be it known that I, WILLIAM PERCY SIMPSON, a citizen of the United States, residing at Overbrook, Montgomery county, State of Pennsylvania, have invented certain new and useful Improvements in Cloth-Winding Machines, of which the following is a specification.

My invention relates to cloth-winding machines, and it has for its object to provide a machine whereby the fabric may be wound into separate rolls without stopping or slackening the speed of the delivery of a continuous web; and to these ends my invention consists in the various features of construction and arrangement of parts having the mode of operation substantially as hereinafter more particularly set forth.

Referring to the accompanying drawings, Figure 1 is a side elevation, partly in section, of a machine embodying my invention; and Fig. 2 is an end elevation thereof.

While my machine is intended more particularly for the winding of cloth, it is obvious that it may be utilized for winding paper or other fabrics, and while I shall describe it in connection with cloth-winding I do not intend thereby to limit the invention to such uses, as the general features thereof are adapted or can be adapted by slight changes by those skilled in the art for many and various purposes.

It is well known that in the dyeing, printing, drying, singeing, shearing, finishing, or other processes through which textile fabrics are passed in their course of manufacture it is desirable and customary to wind the fabrics into rolls for convenience of handling or other purposes, and it is common to use spindles, shells, or rollers, usually of wood, upon which the fabrics are wound, and these rolls usually contain a large amount of goods, often from one to two thousand yards, more or less, as the case may be. The goods to be wound are usually delivered from various machines or apparatuses in which they are being treated in a continuous web, and it is desirable to provide some means whereby the fabric can be wound upon a roller until it has received the desired quantity, and can then be severed and another portion wound upon another roller without stopping or slowing down the

machine or apparatus from which it is delivered to the winder. Heretofore this has generally been considered necessary, as otherwise, after one roll is filled and the fabric severed, a considerable quantity or length of the loose end of the fabric will be delivered onto the floor or otherwise before it is possible to put a new roll in place and start the winding of the fabric, and even then the end of the fabric is often doubled in or so applied to the roll that it becomes creased or wrinkled, which injures the quality of the fabric, and besides that, it is very liable to become soiled where it comes in contact with the floor or machinery, and it is with the object of providing a machine to avoid all these objections that my invention is primarily made.

The construction hereinafter described provides a means whereby a true tight roll of fabric can be readily made, the fabric can be evenly cut when the roll is filled, the end of the fabric can be turned and started around the shell or roller to form a new roll, so as to avoid creasing and prevent the fabric coming in contact with anything which would be liable to injure it, and the operation can be carried on continuously, and the whole is accomplished by a relatively simple, cheap, and effective mechanism, which has proved to be a decided advantage in the handling of textile fabrics.

With this general statement I will now proceed to describe the general principles of my invention, referring to the embodiment thereof shown in the accompanying drawings, it being understood that the details of construction and arrangement of parts can be varied according to the requirements of any particular case without departing from the general principles of my invention.

The machine comprises a suitable frame X, which may be of any desired material and configuration, upon which are mounted a series of rolls or drums, as A A' A'', three being shown in the present instance and being sufficient to carry out my invention. These drums or rolls may be of wood or metal and are geared or connected to be driven from some suitable source of power, and I have shown in the present instance a band-wheel A³, connected to the shaft of one of the drums, and gears A⁴ and pinions A⁵, by means of which all of the drums

will be driven in the same direction and preferably have the same surface speed, which speed is preferably slightly greater than that of the delivery of the fabrics to be wound. In the 5 present instance I have shown the drum A^2 as being slightly below the plane of the other drums, as this is a convenient arrangement for the delivery of the rolls of fabric, but is not an essential or necessary feature of my invention.

The shells D upon which the fabrics are to be wound may be made of wood or other material, and are preferably each provided with a metal shaft C, which passes through the axis 15 of the shells and form end bearings to support the shells while the fabrics are being wound and to support the rolls of fabric while they are being unwound or passed to other machines or apparatus to be properly treated.

20 In order to normally hold the shells in proper relation with the winding drums, some suitable guides should be provided, and I have shown in the present instance V-shaped guiding-supports E, which are arranged at the ends 25 of the shells and receive the bearing ends of the shafts C, and which are shown as connected to rods E' arranged to slide vertically in guides E², on the frame of the machine, and normally held under stress of springs or weights E³, 30 which tend to raise the supports, although the springs or weights are not of sufficient power to raise the support and shell when in position in the supports. These rods are also provided with some means of limiting their upward 35 movement, as for instance, the pin or projection E⁴, which in the present instance comes in contact with one of the guides E² and prevents the supports from rising beyond a certain definite position.

40 Some means should be provided whereby the shells or rollers may be held against the face of the drum or drums under proper tension to insure the proper winding of the fabrics, and I have shown the frame of the machine as being provided with two upright guides B B, one at either side, in which are arranged to slide the weights F. These weights are provided with some means whereby they may be adjusted or moved in operating the 45 machine, and I have shown them as being provided with toothed racks F', which are engaged by pinions F², mounted on a shaft F³, extending between the upright guides and provided with some means for operating them, as the hand-wheel F⁴. Any suitable way of mounting these weights may be utilized; but I have found it convenient to provide the guides with ribs or projections B', between which the weights slide in the guides, and to hold 50 them in position by rods or bolts B² passing through the weights and through slots B³ in the upright guides. The lower ends of the weights are preferably provided with inverted U-shaped bearings f, which are adapted to fit 55 upon the upper faces of the end bearings of the shafts C of the shells, and to thus hold the shells under proper pressure against the

winding-drum, but rising with the drum as the roll of fabric increases as the operation proceeds, in the manner hereinafter set forth. 70

While the use of a tension device, substantially as above described, is an advantage in some instances in winding certain materials, it is not absolutely necessary to use it in all cases, as the weight of the roll itself is sufficient to properly compact the material, and in that case the tension device may be omitted.

When the roll of fabric attains a sufficient size (as indicated by the circle 1) the tension-weights are raised by means of the hand-wheel 80 or otherwise, and the shell having risen beyond the V-shaped supports, which are prevented from following the shell beyond a certain distance, the roll falls by gravity against the second drum A', and is supported and 85 driven for a short time by the two rolls A A', (as indicated by the circle 2) and is from there passed onward by hand or otherwise, so that it is supported by the second and third drums, as A' A², (as indicated by the circle 3) while 90 it continues to be rotated by these drums, continuing the operation of winding until it attains the full size desired, (as indicated by the circle 4,) when it is ready for removal. Meanwhile, after the first roll has passed to 95 the last position indicated, the operator inserts a new shell for the next roll, and this is readily done by placing the shell in the V-shaped supports which are now in their uppermost position (as indicated at 5) and bringing the weights down upon the shell until it 100 occupies the position 6, ready to commence the winding process, and it is now necessary to sever the fabric and start one of the severed ends of the fabric around this second shell, 105 and this I am enabled to do without stopping the moving fabric, and without loss or damage thereto, by the mechanism which I am about to describe.

Mounted in suitable guides, as G, attached 110 to the frame of the machine is a slide H, which can be moved in the guides by any suitable means, as by the lever H', connected to the slide by a link H² or otherwise. Mounted on this slide, preferably at the top, is a knife 115 or cutter I, and this is preferably arranged at an angle, substantially as indicated in the drawings, and is provided with pointed teeth, so that when the knife or cutter is raised at the proper time by the lever or otherwise, the 120 fabric comes in contact with the points of the teeth of the knife, and being under tension it is quickly and evenly severed, and one end passes on and is wound upon the first roll by the drums A' A², while the other severed end 125 is wound around the second shell in position against the periphery of the first drum to make a new or second roll of fabric. In order that this free end of the fabric may be properly guided and started on its shell without 130 being creased, wrinkled, or otherwise injured, I provide a guide J, which tends to direct the free end around the shell, and while this guide may be variously formed and arranged, in

the present instance I provide a bar J' , which is mounted on spring-arms J^2 , which are connected to the slide H , so that the guide moves simultaneously and concurrently with the knife I . These arms J^2 may be of spring material themselves, as indicated in Fig. 1, or may be of other material controlled by a spring, as J^3 , Fig. 2, the essential feature being that the guide-bar J' , shall be free to follow the periphery of the shell and guide the fabric around the same, as clearly shown in dotted lines in Fig. 1. I find it convenient also to provide inclined guides K , which shall direct the movements of the guide-bar J' , so that as it rises with the knife it will immediately catch the severed end of the fabric and follow the surface motion of the shell, insuring the fabric being wound closely around the shell in starting a new roll.

While I have shown the knife and spring-guide as being connected to the same slide and operated by the same mechanism, it is evident that they could be independently operated, although as the operations of the knife and guide succeed each other, it is preferable to operate them in the manner indicated. As soon as the pressure is removed from the lever H' the slide will be restored to its normal position and the spring-guide and knife assume the position indicated in full lines and the fabric continues to wind upon the new roll as before.

Having thus described one embodiment of my invention, it will be seen that the general principles thereof can be carried out in many and various detailed constructions, and it will further be seen that the operation is continuous and there is no waste or injury to the fabric being wound. I may say that it is not absolutely necessary to use the V-shaped supports E , as the shell may be held in proper position by the U-shaped bearings in the weights alone; but I have found it convenient to use the supports to aid in placing shells in position, as well as to serve as additional means of supporting the bearings of the shells to aid in insuring a perfect wind of the fabric.

What I claim is—

1. In a winding machine, the combination with a series of drums, of a shell around which the fabric is wound in contact with one of the drums, and means whereby when the shell has received sufficient fabric it is permitted to move into contact with and be rotated by two of the drums, substantially as described.

2. In a winding machine, the combination with a series of three drums, of a shell around which the fabric is wound in contact with one of the drums, and means whereby when the shell has received sufficient fabric it is permitted to move into contact with and be rotated by two of the drums, and then be moved out of contact with the first drum, and be rotated by two of the drums other than the said first drum, substantially as described.

3. In a winding machine, the combination

with a series of drums, of a shell around which the fabric is wound in contact with one of the drums, and supports for said shell for maintaining it in contact with said drum until the roll has attained a certain size, then permitting it to move into contact with and be rotated by two of the drums, substantially as described.

4. In a winding machine, the combination with a series of drums, of a shell around which the fabric is wound in contact with one of the drums, and supports for the shell having a limited movement whereby when the shell has received sufficient fabric it is permitted to move into contact with and be rotated by two of the drums, substantially as described.

5. In a winding machine, the combination with a series of drums, of a shell around which the fabric is wound in contact with one of the drums, means whereby when the shell has received sufficient fabric it is permitted to move into contact with and be rotated by two of the drums, and means for severing the fabric, substantially as described.

6. In a winding machine, the combination with a series of drums, of a shell around which the fabric is wound in contact with one of the drums, means whereby when the shell has received sufficient fabric it is permitted to move into contact with and be rotated by two of the drums, means for severing the fabric, and means for guiding the severed end around a shell to start a new roll, substantially as described.

7. In a winding machine, the combination with a series of three drums rotating in the same direction, of a shell around which the fabric is wound in contact with one of the drums, means whereby when the roll has attained a proper size it is permitted to move into contact with and be rotated by two of the drums and can be further completed by being rotated by two of the drums other than the first winding drum, means for severing the fabric a second shell, and means for starting the severed end of the fabric on said second shell, substantially as described.

8. In a winding machine, the combination with a series of drums rotating in the same direction, of a shell around which the fabric is wound in contact with one of the drums, a tension device for the shell, means whereby the partly wound shell may be released from the tension device and permitted to move into contact with and be rotated by two of the drums, means for severing the fabric, and means for guiding the severed end of the fabric around a shell, substantially as described.

9. In a winding machine, the combination with a series of drums, of a shell around which the fabric is wound in contact with one of the drums, an adjustable tension device for said shell for holding it in contact with one of the drums, and V-shaped supports for the shell having a limited movement, substantially as described.

10. In a winding machine, the combination

with a series of three drums, of a shell around which the fabric is wound in contact with one of the drums means whereby the shell is permitted to move into contact with and be rotated by two of the drums and then the winding continued in contact with drums other than the first winding drum, a reciprocating frame, a knife carried by the frame for severing the fabric, and a spring-guide also carried by the frame for directing the severed

end around the shell, substantially as described.

In testimony whereof I have signed my name to this specification in the presence of two subscribing witnesses.

WILLIAM PERCY SIMPSON.
